US0D1011882S

(12) **United States Design Patent** (10) **Patent No.:** **US D1,011,882 S**
(45) **Date of Patent:** **** Jan. 23, 2024**

(54) **BEVERAGE CUP LID HAVING A CONDIMENT CONTAINER RECEPTACLE SET**

(71) Applicants: **Nicole Elarde**, Commack, NY (US); **Justin Macari**, St. James, NY (US); **John Elarde, II**, Commack, NY (US); **John Elarde, III**, Commack, NY (US); **Joseph Elarde**, Commack, NY (US); **Julia Elarde**, Commack, NY (US)

(72) Inventors: **Nicole Elarde**, Commack, NY (US); **Justin Macari**, St. James, NY (US); **John Elarde, II**, Commack, NY (US); **John Elarde, III**, Commack, NY (US); **Joseph Elarde**, Commack, NY (US); **Julia Elarde**, Commack, NY (US)

(**) Term: **15 Years**

(21) Appl. No.: **29/824,694**

(22) Filed: **Jan. 26, 2022**

(57) **CLAIM**

The ornamental design for a beverage cup lid having a condiment container receptacle set, as shown and described.

DESCRIPTION

FIG. 1 is a top plan view of a beverage cup lid having a condiment container receptacle set in accordance with the present invention;

FIG. 2 is a top perspective view thereof; and,

FIG. 3 is a bottom perspective view thereof.

The broken lines shown in the drawings illustrate portions of the beverage cup lid having a condiment container receptacle set that form no part of the claimed design.
